UNITED STATES PATENT OFFICE.

HENRY B. RIEHLÉ, OF PHILADELPHIA, PENNSYLVANIA, ASSIGNOR OF ONE-HALF TO FREDERICK A. RIEHLÉ, OF SAME PLACE.

WEDGE-CLAMP.

SPECIFICATION forming part of Letters Patent No. 249,259, dated November 8, 1881.

Application filed May 20, 1881. (No model.)

To all whom it may concern:

Be it known that I, HENRY B. RIEHLÉ, of Philadelphia, in the county of Philadelphia and State of Pennsylvania, have invented a new and useful improvement in a wedge of peculiar shape, to be used in holding boiler-plate or flat specimens in a testing-machine, or be applied for other purposes to resist a strain, of which the following is a specification.

10 The object of my invention is to obtain a perfectly central pull or stress on flat material without the possibility of tearing from the sides or edges, a difficulty heretofore existing in wedge-gripes generally.

15 My invention consists of a wedge having its cut face which gripes the specimen slightly raised through its center longitudinally its entire or partial length. The center line can be approached either by a curve or in a straight manner.

I am aware that wedges with curved backs, and wedge seats or lines with backs or faces arched are made to accommodate specimens of uneven thickness. They, nevertheless, will 25 not prevent a twist or torsion if opposite corners of specimens above and below are unequal in thickness or the surfaces are harder, or if teeth of wedges are worn away unevenly, allowing slipping or shifting of the specimen 30 also. In my improved wedge the specimen is engaged at once through the axial line, and presses continuously a little harder at the center (throughout the entire test) than it does on the edges. The edges are thus relieved under all

circumstances, and a side pull causing a tear 35 is impossible, and any danger from a twist prevented. I do hereby declare that the following is a clear, full, and exact description thereof, reference being had to the accompanying drawings, in which similar letters and figures 40 indicate like parts.

Figure 1 is a plan view of an ordinary specimen holder or clamp. Fig. 2 is a vertical sectional view, and Fig. 3 is a modification of the wedge-face.

45 The clamp A is held in position in the machine by the bolts B B.

In Figs. 1, 2, and 3 C C represent the wedges. In Fig. 1 the faces of wedges C C, which press against the specimen D, are curved, while in 50 Fig. 3 the faces are straight to the center line. Both are shown more curved or inclined than in reality.

The letters e on Figs. 1 and 2 represent a steel pin held by a set-screw, which acts as a 55 guide in upper and lower clamp, to bring specimens to the center perpendicularly.

What I claim as my invention is—

A wedge adapted to hold flat bars in a testing-machine, having its vise or biting-face 60 throughout its entire length, or a portion thereof, raised in a central longitudinal line, substantially as described, and for the purpose set forth.

HENRY B. RIEHLÉ.
